BOARD, BALL AND PADDLE GAMES

Donald Christian, Tacoma, Wash.

Application August 1, 1955, Serial No. 525,459

2 Claims. (Cl. 273—123)

This invention relates to a novel ball game employing paddles manipulated by opposing players to drive the ball back and forth across a game board in an effort to evade the opponent's paddle and pocket the ball at the opponent's end of the board for scoring purposes. The invention is herein illustratively described by reference to the presently preferred forms thereof; however, it will be recognized that certain variations and modifications therein, especially with respect to details may be made without departing from the patentable subject matter involved. The present application for patent is a continuation-in-part of application Serial No. 386,205, filed October 15, 1953, now abandoned.

The highly popular game of Ping-pong is a fast delightful game but one requiring a certain amount of skill for a player even to participate. Also it is a game requiring a considerable floor area and the activity of the game is such that the participating players must stand up in order to play successfully. It is unplayable out of doors if the wind is blowing very strongly because of the very light weight of the Ping-pong balls.

The present invention provides a game which is equally as fast and delightful if not more so in some respects than the game of Ping-pong and which overcomes the above-described limitations of the latter game. That is, the novel ball and paddle game herein disclosed offers significant therapeutic values, it has an interesting and engaging appeal conducive to relaxation, and it offers a type of non-strenuous exercise providing for coordination and dexterity development. It requires only a comparatively small amount of floor area in which to be played, it permits the board to be placed on the floor or in an elevated position so that the players may sit, kneel or stand according to their own choice, and it can be played equally well indoors or out of doors, for the factor of wind presents no problem.

Another and highly important object of the invention is such a game which can be played by small children, invalids, victims of cerebral palsy, etc., as well as by active adults and youths, and which without any previous skill or training in its play can be enjoyed by any and all of such persons. Although skill is not required to enjoy the game, skill can be acquired in its play. Nevertheless, it is a game in which a skilled player can enjoy playing against a relatively unskilled player and vice versa.

In view of the foregoing and other objects and the fact that the game can readily be manufactured at relatively low cost and in a highly rugged and durable form, it is ideally suited for use in grammar schools, nurseries, hospitals, therapeutic wards, etc., as well as in individual homes.

With the foregoing and other objects in view the invention in brief terms comprises the combination of a set of paddles and a suitable missile, preferably a small wooden ball about the size of a medium-size marble, which is struck by said paddles back and forth across the game board, the latter being the principal characterizing implement of the game. Such game board of generally rectan-

2

gular proportions, has a substantially flat playing surface and a retaining rail extending substantially around the entire perimeter thereof. A dividing bar extends across the width of the board intermediate the ends thereof at a spacing above the playing surface somewhat to exceed the ball diameter. One or more openings or pockets formed in opposite ends of the board adjacent the rail and individually occupying a small fraction of the board's total width, serve as the goals for the ball in building up a game score.

The paddles are of generally elongated form, one end being provided with a handle and the opposite end being provided with a substantially straight, transverse edge which is intended to be slid or scraped on the playing surface of the board with the paddle held in upright position in striking or intercepting the ball. The object in general is to drive the ball past the opponent's paddle and into one or another of the goal openings or pockets on the opponent's side of the board, using direct and bank shots as may best suit the continuously changing nature of the play. The ball must not be driven over the retaining rail, nor must it pass over the center bar in approaching a pocket in the opponent's end of the board if the score is to count.

These and other features, objects and advantages of the invention will become more fully evident from the following description thereof by reference to the accompanying drawings illustrating the preferred embodiments.

Figure 1 is a perspective view of the game board structure in one form.

Figure 2 is a longitudinal sectional view of the game board taken on line 2—2 in Figure 1.

Figure 3 is a perspective view of a paddle used in playing the game.

Figure 4 shows a wooden ball forming the missile or playing element.

Figure 5 is a fragmentary plan view of a modified game board structure.

Figure 6 is a fragmentary detail of the game board structure taken on line 6—6 in Figure 5.

Figure 7 is a fragmentary detail section through the game board structure taken on line 7—7 in Figure 5.

Referring to Figures 1 and 2, the illustrated game board 10 comprises the generally rectangular flat bottom panel 11 formed of "Masonite," plywood or other suitable material, and is preferably about two and one-half feet wide and four feet long. A side rail 12 extends around the entire periphery of the playing board and projects upwardly perpendicular to its playing surface about two and one-half inches. This rail serves as a bank and retainer wall for the game missile rolled about on the flat playing surface of the board.

Pocket openings and pockets 13, 15, 16 and 18 are formed in the respective corners of the playing board, and pocket openings and pockets 14 and 17 are formed in opposite ends of the board intermediate the sides thereof adjacent the bank rail. Preferably all of these pockets are of about the same size, materially exceeding the size of the ball and individually occupying a small fraction of the total width and length of the board, as shown.

An elevated divider bar 24 is mounted on the game board to extend across the width of the board intermediate its opposite ends at an elevation above the playing surface somewhat exceeding the diameter of the ball to be used in the game. In order for a player to score by causing the ball to drop into one of the pockets at the opponent's end of the board such ball must pass beneath the divider bar 24.

The support for the board comprises the transversely extending underlying bars 21 and 22 situated adjacent the inner sides of the end pockets and elevating the playing surface of the board with respect to an underlying support surface such as a floor or table top (not

shown) sufficiently to accommodate the hanging pockets themselves. An underlying brace bar 23 extends longitudinally of the board between the supporting rails 21 and 22 at a location intermediate the side edges of the board. This brace bar stiffens the playing board panel and also braces the supporting rails 21 and 22.

The game paddle, as shown in Figure 3, has a generally rectangular flat paddle surface 26 for striking the ball, and a handle 27. Preferably the end edge of the paddle opposite the handle is a substantially straight edge about two and one-quarter inches long. The playing missile is preferably in the form of a round wooden ball about the size of a marble (about three-quarters of an inch in diameter) it being recognized that other materials approximately equivalent to wood in resilience and density may be substituted therefor. The game has a very satisfactory pace when a wooden ball is used whereas a heavy metal ball would be unsatisfactory as would a ball as light as a Ping-pong ball. Rubber would also not be as satisfactory as wood. It will be noted that the pace of the game is in large measure determined by the properties of the game missile for bouncing from the paddle and also for bouncing from the bank rail 12, in executing bank shots and off the end sections of the rail.

In playing the game the players stand, kneel or sit at opposite ends of the board and, holding a paddle in one hand, alternately drive the ball 25 back and forth across the length of the board, using bank shots and direct shots in an attempt to pocket the ball in one of the pockets at the opponent's end of the board. Since it is somewhat easier to pocket the ball in the corner pockets, these are preferably assigned a relatively low score such as one point, whereas the intermediate pockets 14 and 17 make somewhat more difficult goals and are assigned a higher score such as a count of two points. The first player to reach the total score of 21 or some other grand total is the winner.

It is preferred as a rule of the game that the paddle must be held in an upright position with its lower edge extending parallel to and normally contacting the playing surface of the board. The center bar 24 is a definite dividing line which must not be passed by the player's hand or paddle, lest a penalty, such as a free shot, be assigned. A free shot is also assigned if one of the players knocks the ball over the side rail or, optionally, if one of the players knocks the ball over the dividing bar 24. In any event, if a player causes the ball to pass over the dividing bar in approaching an opponent's pocket, the score does not count if the ball happens to drop into the pocket on that shot. In all cases a penalty free shot cannot be resisted by the opponent, nor the ball touched until the ball has struck and bounced from the end rail at the opponent's end of the board. Preferably also the ball or marble can be stopped at any time with the paddle so as to execute a shot toward the opponent's end of the board with the ball stationary. Neither the hand nor arm can be used to block goals nor to stop a marble, nor to execute a shot. If one player knocks the ball over the side rail without the ball being touched by the other player or his paddle, then the latter, instead of having a free shot, may, optionally in the establishment of rules, have the privilege of serving the ball.

In the modified form of the playing board shown in Figures 5, 6 and 7, the playing board panel 11' is surrounded by the side rail 12' as in the previous example, and has pocket openings therein at the corners and intermediate pocket openings at the end edges of the board. The pocket openings at one end of the board are shown in Figure 5, being designated 13', 14' and 15', respectively. Also the board is supported by transverse rails, the rail 22' being shown in Figure 5 extending widthwise of the board adjacent the inner edges of the pocket openings at that end of the board. A similar rail extends across the width of the board near the opposite end thereof. In addition, the board has two transverse rails 30 located

generally between the middle of the board (measured lengthwise) and the respective ends thereof to provide additional support and stiffening for the board. In this case no longitudinal brace is used beneath the board as in the previous example. Only one of the intermediate transverse rails 30 appears in Figure 5. This rail is also shown in Figure 7. A principal difference between the modified board shown in Figures 5, 6 and 7, and that shown in the preceding figures is in the manner of forming the pockets. In this case the pockets are formed by extending the side rail 12' below the playing board panel 11', by a distance somewhat less than the ball diameter, and short of the projecting width of the transverse support bars 22', etc. An elongated horizontally disposed strip 32 is then fastened across the full width of the board to close the gap between the end section of rail 12' and the adjacent support bar 22' or its counterpart at the opposite end of the board. Preferably the strip 32 is rabbeted in the side of support bar 22' and is nailed to the underside of the side rail downward extension, as shown in Figure 6. Thus a single strip extending across the full width of the board forms a bottom for all of the pockets at that end of the board and also serves as a stiffener or brace for the adjacent support bars such as the rail 22'. This means of forming the pockets, of stiffening the board and of bracing the support rails is an inexpensive feature of construction.

These and other possible variations in the details of construction of the board will be apparent to those skilled in the art, but in all cases it will be evident that a novel, exciting and relaxing game having considerable versatility and therapeutic value is provided and that the objects and purposes described hereinabove are met by the disclosed game implements.

I claim as my invention:

1. A ball and paddle game comprising a set of paddles individually formed to be held in one hand each by an opposing player, a ball of small size in relation to said paddles, and a relatively large game board comprising a panel of generally elongated rectangular proportions having a playing surface which is flat throughout the extent of said board and across which the ball is rolled back and forth when struck by the paddles during play, a ball-retaining rail extending substantially around the entire perimeter of said playing surface and having an inside face projecting upwardly from the plane of the board in generally perpendicular relationship therewith to serve as a bank from which the ball bounces on impact therewith, and an elongated divider element mounted on said game board to extend across the width thereof intermediate the ends of such board at an elevation above said playing surface permitting said ball to pass freely therebeneath, said panel having one pocket opening therein at each of its four corners and at least one pocket opening therein at each end generally intermediate the corner pockets, said pockets all being formed by openings in said game board panel adjacent said rail and of a size at least several times the size of the ball, such openings having a dimension measured widthwise of said panel which is at least a plurality of times the ball's diameter but is a small fraction of the board's width.

2. A ball and paddle game board comprising a panel of generally elongated rectangular proportions having a playing surface which is flat throughout the extent of said board, a ball-retaining rail extending substantially around the entire perimeter of said playing surface and having an inside face projecting upwardly from the plane of the board in generally perpendicular relationship therewith to serve as a bank from which the ball bounces on impact therewith, and an elongated divider element mounted on said game board to extend across the width thereof intermediate the ends of such board at an elevation above said playing surface permitting said ball to pass freely therebeneath, said panel having one pocket opening there-

in at each of its four corners and at least one pocket opening therein at each end generally intermediate the corner pockets, said pockets all being formed by openings in said game board panel adjacent said rail, such openings having dimensions measured widthwise and lengthwise of said board which are material fractions of the board's width and length respectively, whereby the openings are adapted to trap a ball rolling rapidly across them.
